AMALGAM PRESS

George B. Eberenz, San Francisco, Calif.

Application March 3, 1938, Serial No. 193,619

2 Claims. (CL. 32—40)

This invention relates to an improved amalgam press.

When an amalgam is prepared, usually there is an excess of mercury in liquid form that is not amalgamated with the solid metallic ingredient. For instance, when a dental amalgam of mercury and silver is prepared, excess liquid mercury is commonly present. Heretofore, it has been a difficult operation to remove excess mercury and to produce a perfect amalgam. When an amalgam having excess free mercury is used for filling teeth, the quality and the life of the filling may be seriously impaired. Further, such an amalgam does not lend itself properly to the operation of filling teeth. Excess mercury may, in some instances, be forced from the amalgam by the "plugging" tool used to pack the filling into the cavity.

It has been common practice to attempt to squeeze excess mercury from dental amalgam, by hand, which is not efficient and may contaminate the amalgam.

It is a primary object of the present invention to provide a press that can be advantageously used to remove excess mercury from any type of amalgam that is prepared for any purpose.

A further object is to provide a press of this character that can be disassembled readily for filling, cleaning and repairing, as well as removing the amalgam.

Other objects and advantages reside in details of design and construction, inclusive of means for eliminating handling of the amalgam, which will be more fully disclosed in the following description, and in the drawing wherein,

Figure 1 is a plan view of an amalgam press built according to a preferred form of the present invention;

Figure 2 is a longitudinal section of the same; and

Figure 3 is a transverse section taken on line 3—3 of Figure 2.

In the drawing, reference character 5 denotes a cylinder in which is operably positioned a piston or plunger 6 that terminates in a hand-piece 7. One end of the cylinder is covered by means of a screwed cap 8, which effects a sealed closure around the piston by means of a packing gland 9. The cap 8 is concave as at 8a, forming a funnel for the cylinder to facilitate pouring amalgam into the press when the piston is withdrawn. The other, or discharge end of the cylinder is covered by another screwed cap or nut 10 that holds a swivel nozzle 12. Securely clamped across the discharge end of the cylinder is a filtering

medium, such as a disk of chamois skin 13, that is preferably supported by a screen-like perforated plate 14, both of which are interposed between the bore of the cylinder 5 and the hole in the nozzle 12. Since the form of the invention illustrated is intended for hand use, a finger bracket 15 is provided on the cylinder for the convenience of the operator.

In use, the piston or plunger 6 is withdrawn to empty the bore of the cylinder which is then to be filled with the amalgam, by pouring it through cap 8.

After the amalgam has been placed in the cylinder, the plunger or piston 6 is forced inwardly, whereupon liquid mercury is pressed from the amalgam through the chamois 13, the screen-plate 14, and may be returned to a mercury container by means of the nozzle 12. The nozzle is flanged as at 12a so that in assembling the filter element onto the cylinder, the nut or cap 10 will turn while the flange of the nozzle will hold the filter parts securely in place without turning them, which might distort the chamois. While the filter supporting element 14 has been shown as a perforated plate, a wire screen of suitable strength or any other screen element may be used.

As hereinabove mentioned, the form of the improved amalgam press illustrated and described, is intended for hand use and primarily for service in a dentist's office or in a dental laboratory. However, it will be readily understood that presses built according to this invention may be constructed on a much larger scale for industrial purposes, and well-known mechanical means may be used to force the compressing piston into the cylinder instead of the hand-power plunger shown.

Preferably, all parts of the improved amalgam press should be made of material that will not amalgamate with mercury, such as stainless steel.

The filtering medium, which, in preferred form, is a disk of chamois skin, serves the dual purpose of a filter and a gasket to aid the leak-proof closure of the nozzle end of the cylinder.

When used in dental work, the press has the further advantages of permitting an operator to prepare an economical small amount of amalgam at one time and it eliminates all necessity for having the amalgam come in contact with human hands, which might contaminate it.

After all excess liquid mercury has been pressed from the amalgam, the cap 10, filter 13 and screen 14 may be removed, and the amalgam

in its finished form may be ejected from the cylinder 5 by means of the piston 6, and the former method of hand handling or pressing is thus dispensed with. Even a slight contamination of dental amalgam, as from natural oil from the hands, may impair the quality of the filling.

What I claim and desire to secure by Letters Patent is:

- 10 1. A device of the character described comprising an open end cylinder, a piston slidably fitted therein, a disk filter element positioned against the open end of the cylinder across the opening therein, a similarly shaped filter-supporting screen element positioned adjacent the filter element, a swivel discharge nozzle for the cylinder, and a threaded cap-nut on the cylinder for drawing the nozzle, the filter element and the filter screen toward the open end of said
- 15

cylinder without rotation of said nozzle or filter element.

2. A device of the character described comprising an open end cylinder, a piston slidably fitted therein, a disk filter element positioned against the open end of the cylinder across the opening therein, a similarly shaped filter-supporting screen element positioned adjacent the filter element, a flanged discharge nozzle positioned with said flange adjacent the filter-supporting screen, and a threaded cap nut rotatably positioned around the nozzle in threaded engagement with the cylinder for drawing said nozzle toward the cylinder whereby the screen and the filter are clamped between the flange and the cylinder without rotation of the flange or filter.
